UNITED STATES PATENT OFFICE.

CHARLES EDGAR MANNERS, OF GLENVILLE GLEN, CRAFTERS, SOUTH AUSTRALIA,
AUSTRALIA.

SPRING.

1,405,606.

Specification of Letters Patent. Patented Feb. 7, 1922.

Application filed August 26, 1920. Serial No. 406,099.

To all whom it may concern:

Be it known that I, CHARLES EDGAR MANNERS, a subject of His Majesty the King of Great Britain, residing at Glenville Glen, 5 Crafters, in the State of South Australia, in the Commonwealth of Australia, have invented certain new and useful Improvements in and Connected With Springs, of which the following is a specification.

10 My invention relates to improvements in and connected with springs and is intended to apply more particularly to what are termed coil springs and half-coil springs for furniture and upholstery and for the 15 cushions of motor cars and the like.

Hitherto springs of this nature have usually been held in position by strips of webbing to which they have been stitched or to a lining of Hessian or other fabric, and more 20 recently cross wires have been introduced into the structure to which the springs have been attached by metal clips.

The special object of my invention is to construct the springs in such a manner that 25 they contain means for attachment to the wires of the frame as an integral portion of the spring, an auxiliary attachment being provided if so desired to assist in keeping the springs in their relative positions.

30 In carrying my invention into effect I form loops, recesses or hook-like structures in suitable positions by twisting or bending the spring substantially in the manner hereinafter described and as illustrated in the 35 accompanying drawings wherein:

Fig. 1 is a side elevation of a spring.

Fig. 2 is a plan of Fig. 1.

Fig. 3 is a plan of a spring showing different arrangement of the bent or looped 40 portions for use with parallel frame wires.

Fig. 4 is a plan of a spring with loops for cross wires also showing attachment to an adjacent spring.

Fig. 5 is a side elevation of a spring showing cross wires engaged in loops or kinks.

Fig. 6 is a side view of a spring showing cross wires engaged in hook-like formations which are bent upon inturned top and bottom ends of the spring wire.

50 Fig. 7 is a plan showing the upper portion of spring with inturned end and also showing portion of lower inturned end, the bent portion of lower end being omitted.

Fig. 8 illustrates the hook portion of in- 55 turned end before the hook is finally bent.

Fig. 9 illustrates the hook portion of in-turned end after it has been finally bent and cross wires inserted.

In each of the illustrations similar letters of reference are used to denote similar or 60 corresponding parts wherever they occur.

In the drawings the coils of the wire spring are indicated by the reference letter *a*, the spring being either of spiral construction as in Fig. 1 or it may consist of rings of equal 65 diameter as in Fig. 6.

In Figs. 1, 2 and 4 I have illustrated loops or eyelets *b* arranged at right angles round the periphery of the spring wire by merely bending the wire upon itself as clearly indicated, the loop thus formed being of just sufficient diameter to accommodate the cross wire *c*. In Fig. 3 I have shown two similar loops opposite to each other, but the corresponding loops which are at right angles are 75 twisted or deflected outwardly so that if the frame is built up of parallel wires they can readily be accommodated in the side loops as will be well understood.

It may not always be necessary or convenient to form complete loops or eyelets in the periphery of the wire and I have therefore provided for the accommodation of the cross wires in kinks or recesses correspondingly marked *b* in Fig. 5 and likewise 80 arranged at right angles to each other. These are preferably bent alternately upwards and downwards, the arrangement being such that the cross wires in combination with the spring interlock each other and prevent displacement without necessitating an additional attachment or binding piece which however may be added if desired.

In Fig. 6 of the drawings and also in Fig. 7 I have illustrated my integral attachment as placed on the extreme ends of the wire which forms the coil spring. With this arrangement the top end of the wire and likewise the bottom end are each bent inwardly towards the centre of the coil. A 95 convenient method of making the loop consists in bending the wire extremity which is indicated at *a*¹ into the form of a hook-end as shown in plan in Fig. 8. The portion which forms the loop is then bent downwards at right angles to the part *a*¹ and the free end marked *a*² in Fig. 8 is also bent downwards parallel to the loop bend so as to form an arch. This structure provides 100 for the accommodation of both cross wires 105 110

in the centre of the spring as will be well understood upon reference to Fig. 9 of the drawings.

In Fig. 4 I have shown a small bridge-piece at *d* for keeping adjacent springs in their relative positions. This bridge-piece is not for attaching the springs to the cross wires but is to prevent their displacement on their mountings as it has been found in connection with some attachments that the springs sometimes work apart and in other cases they come together and cause rattle. The bridge-piece for this purpose may have slots or holes at each end to facilitate its attachment to the structure so that the cross wires will not form an impediment, but it is turned back upon itself so as to embrace the spring wires and can be cleated with the aid of pliers or other implement in order that it may firmly hold the spring wires and thus prevent the relative displacement of the springs.

In Fig. 2 I have illustrated a simple wire connecting piece at *e* which may be used in conjunction with a brad or screw for holding a spring to a wooden or iron frame.

With regard to the upper portion of the spring shown in Fig. 1 it is to be understood that this may be furnished with loops or hooks of the nature already described, or a single or double loop or hook may be

formed thereon, and that the bent or looped end shown in Fig. 8 may be used to support a supplemental attachment.

Having now fully described and ascertained my said invention and the manner in which it is to be performed, I declare that what I claim is—

A device of the character described including upper and lower crossed frame wires 40 extending substantially at right angles to each other, and coiled springs interposed between said upper and lower frame wires and having their axes substantially aligned with the intersecting points of said crossed frame 45 wires, each of said springs being provided with an inwardly projecting end portion bent back upon itself to form a hook having an open end and a closed end, the closed end being substantially below the plane of 50 said inwardly bent portion and an intermediate portion of said hook being arched upwardly to overlie one of said frame wires and at opposite sides of the other cross frame wire, said closed end of said hook being engaged under the last named cross frame wire, whereby the hook and said crossed frame wires are interlocked against lateral displacement.

In testimony whereof I affix my signature.

CHARLES EDGAR MANNERS.
